Primary Examiner—T. Chase Nelson*Assistant Examiner*—Karen Acker(74) *Attorney, Agent, or Firm*—Michael Best & Friedrich LLP(57) **CLAIM**

The ornamental design for the air tool, as shown and described.

DESCRIPTION

FIG. 1 is a perspective view of an air tool.

FIG. 2 is a top view of the air tool shown in FIG. 1.

FIG. 3 is a bottom view of the air tool shown in FIG. 1.

FIG. 4 is a front view of the air tool shown in FIG. 1.

FIG. 5 is a rear view of the air tool shown in FIG. 1.

FIG. 6 is a right side view of the air tool shown in FIG. 1; and, FIG. 7 is a left side view of the air tool shown in FIG. 1.

The broken lines in the drawing represent internal boundaries of the design and unclaimed portions of the design. The broken lines and the areas within the broken lines form no part of the claimed design.

1 Claim, 4 Drawing Sheets
